LEG STRUCTURE FOR COLLAPSIBLE TABLES

William Herrschaft, New York, N. Y.

Application April 26, 1955, Serial No. 503,885

3 Claims. (Cl. 311—109)

This invention relates to new and useful improvements and structural refinements in collapsible tables, stands, and the like, and the principal object of the invention is to provide a table or a stand which may be quickly and easily folded so as to occupy a small amount of space when stored or carried, but which may be erected with equal expedience into a rigid, stable form.

An important feature of this invention resides in providing the table or stand with a novel leg structure utilizing a plurality of substantially V-shaped legs, each having a substantially vertical outer portion and a diagonal inner portion with the inner, diagonal portions of the legs being crossed, while another important feature of the invention lies in the provision of novel means for collapsibly connecting the leg portions together.

With respect to the leg connecting means, attention is also directed to my co-pending application Serial No. 330,981, filed January 13, 1953, now Patent No. 2,749,147, of which this application is a continuation-in-part.

With the foregoing more important objects and features in view and such other objects and features as may become apparent as this specification proceeds, the invention resides in the details of construction and arrangement of parts substantially as shown in the accompanying drawing, wherein like characters of reference are used to designate like parts and wherein:

Figure 1 is a side elevational view of the invention, shown partly in section to reveal the attachment of the table top to the leg structure;

Figure 2 is a horizontal sectional view, taken substantially in the plane of the line 2—2 in Figure 1 and illustrating the table top for reference purposes by dotted lines;

Figure 3 is a perspective view of one of the legs, another leg being shown fragmentarily by dotted lines to reveal its relationship to the leg shown by full lines;

Figure 4 is a vertical sectional detail on an enlarged scale, taken substantially in the plane of the line 4—4 in Figure 2;

Figure 5 is a fragmentary elevational view showing a modified form of the leg connecting means; and

Figure 6 is a fragmentary perspective view illustrating a modified form of means for attaching the legs to the table top.

With reference now to the accompanying drawing in detail, the collapsible table, stand, or the like, is designated generally by the numeral 10 and, broadly, comprises a leg structure 11 carrying a suitable top 12.

The leg structure 11 consists of a plurality of substantially V-shaped legs 13 each having a substantially vertical outer portion 13a and a diagonal inner portion 13b extending inwardly and upwardly from the lower end of the outer portion, as shown.

The diagonal inner portions 13b of the legs 13 are crossed and coupling means designated generally by the numeral 14 are used for connecting the portions 13b together at their point of crossing. These coupling means will be hereinafter more fully described.

2

The outer portion 13a of each leg is provided at its upper end with an inturned, substantially horizontal hook 15 and since the outer portion 13a of each leg is substantially aligned with the diagonal inner portion 13b of an opposite leg, the hooks 15 of the outer portions 13a may be supportably engaged with the upper regions or portions of the respective diagonal portions 13b of the opposite legs, as will be clearly apparent.

The aforementioned coupling means 14 preferably 10 comprise a substantially tubular, resiliently yieldable member in the form of a coil spring 16 which frictionally encircles the leg portions 13b at their point of crossing and urges the same together in a radially inward direction. However, when the legs are spread apart against 15 the action of the spring 16 and the hooks 15 are engaged with the leg portions 13b, the hooks will effectively sustain the legs in the spread apart position and, as a result, the entire leg structure will be rigid and stable. When 20 so desired, the leg structure may be folded by simply disengaging the hooks 15 from the leg portions 13b.

To prevent the spring 16 from excessive radially outward deflection when the legs are spread apart, a substantially tubular reinforcing sleeve 17 is frictionally mounted on the spring and projects at both ends beyond 25 the ends of the latter. The ends of this sleeve are engageable by the leg portions 13b and thus afford stop means for limiting the extent to which the leg portions 13b may be spread apart.

As shown in Figure 4, the sleeve 17 may simply consist of a short length of tubing. Alternatively, it may be formed from relatively stiff wire wound into a helical form, as shown at 17a in Figure 5. In both instances, the end portions of the spring 16 are angulated to provide a pair of hook-shaped detents 18 which engage the upper and lower end portions of the sleeve and prevent axial displacement of the latter relative to the spring. Moreover, when the sleeve 17a is employed, the detents 18 are disposed in seats 19 constituted by the ends of the helix and thus, the spring 16 is prevented from rotating 40 in the sleeve.

It will be apparent from the foregoing that the leg structure 11 is capable of sustaining its erected, stable form, regardless of the presence or absence of the top 12. Moreover, it can do so either in the upright or an inverted 45 position, in the latter instance the free ends of the diagonal leg portions 13b functioning as feet. As such, the same may be provided with suitable foot elements 20 so that the ends of the leg portions 13b do not scratch or otherwise damage the surface on which they are placed.

50 When the leg structure is used in conjunction with the top 12, the top is preferably provided in its corners with recesses or notches 21 to receive the leg portions 13b as shown in Figure 1. The elements 20 then engage the upper surface of the top 12 while the hooks 15 underlie 55 the top, as illustrated.

In a somewhat modified arrangement of the top attaching means shown in Figure 6, the upper ends of the leg portions 13a are angulated as shown at 22 and are suitably secured to corner plates 23 wherein the corner portions of the top are seated. In this arrangement the leg structure is also somewhat modified, since the hooks 15 cannot be provided on the outer leg portions 13a. Thus, the hooks 15 are provided at the upper ends of the diagonal inner portions 13b and supportably engage the upper end regions of the outer portions 13a, as shown. 60 However, apart from this reversal of parts, the operation of the leg structure is the same as already described.

While in the foregoing there has been shown and described the preferred embodiment of the invention, various modifications may become apparent to those skilled in the art to which the invention relates. Accordingly, 65 it is not desired to limit the invention to this disclosure.

and various modifications may be resorted to, such as may lie within the spirit and scope of the appended claims.

What is claimed as new is:

1. In a collapsible table and the like, the combination of a plurality of substantially V-shaped legs each having a substantially vertical outer portion and a diagonal inner portion extending from the lower end of said outer portion, the diagonal inner portions of said legs being crossed and having free upper ends, resiliently yieldable means connecting said diagonal inner portions at their point of crossing whereby the same are urged radially inwardly, and means connecting the upper end of the outer portion of each leg to the upper end of the inner portion of another leg, whereby to sustain the inner portions of the legs against inward radial movement. 5

2. The structure as set forth in claim 1 wherein said last mentioned means comprise hooks provided at the upper ends of said outer portions of the legs and releasably engaging the inner portions. 10

3. The structure as set forth in claim 1 wherein said last mentioned means comprise hooks provided at the upper ends of said inner portions of the legs and releasably engaging the outer portions. 20
